UNITED STATES PATENT OFFICE.

JACOB F. OBERLE, OF RICHMOND, NEW YORK.

SMOKE-HOUSE.

1,152,965.

Specification of Letters Patent.

Patented Sept. 7, 1915.

Application filed April 25, 1914. Serial No. 834,388.

To all whom it may concern:

Be it known that I, JACOB F. OBERLE, a citizen of the United States, and a resident of Richmond, county of Richmond, and 5 State of New York, have invented certain new and useful Improvements in Smoke-Houses, of which the following is a full, clear, and exact description.

This invention relates more particularly 10 to a smoke-house for smoking meats of different kinds.

It is customary to build or place the smoke-house in tenement houses and usually in the basement thereof. For sanitary reasons, it is necessary that the smoke-house be constructed so that access may be had to the portion wherein the meats are smoked and that this be accomplished without the smoke escaping into the basement and into other 20 portions of the building. So far as I am aware, many objections have been raised to smoke-houses or apparatuses of this kind as ordinarily constructed because of their inaccessibility and lack of satisfactory provision 25 whereby the smoke may be caused to pass directly from the smoke-house or apparatus to the chimney or flue without escaping to the outside thereof with the objectionable features necessarily arising therefrom.

One of the principal objects of the present invention is to overcome the objections above named and to provide a smoke-house or apparatus which may be placed within a building or which may be constructed or built as a part thereof and so constructed that means may be readily and effectively smoked without the liability of any smoke passing to the exterior of the smoke-house or apparatus 35 and in which access may be readily had at will to the interior thereof to place the meat to be smoked within the same or to remove the meat after being smoked from the apparatus.

Another object of the invention is to provide a simple and efficient smoke-house or apparatus whereby the access doors to the interior of the smoking compartment may be positively locked and held against movement so long as the smoking of the meat is underway, and in which all openings from the apparatus are so controlled that free

passage of the smoke to the chimney or chimneys is provided for and which controlling means are operated simultaneously with the locking and unlocking of said doors.

Other objects of the invention are to provide a smoke-house having inner and outer compartments and means for controlling the exit of smoke from said compartments; 60 to provide means for closing the fire-box to prevent smoke passing therefrom into the smoking compartment or to open said means to form a communication between the smoking compartment and the fire-box; to provide simple and efficient means whereby the fire-box smoke exit openings may be controlled and communication between the smoking compartment and the flues also controlled and the access doors to the smoking compartment automatically locked or unlocked according to the position of the controlling means of the exit openings; to provide an apparatus having a smoking 65 compartment and an outer smoke chamber 70 or compartment each communicating by independent flues to a chimney or chimneys; and to provide means whereby the smoking compartment may be under positive control.

A further object of the invention is to 80 provide simple and efficient mechanism whereby all the smoke exit openings may be simultaneously actuated.

A still further object of the invention is to provide a smoke-house or apparatus which 85 is simple in construction and which is effective in use.

With these and other objects in view, the invention will be hereinafter more particularly described with reference to the accompanying drawings, which form a part of this specification, and will then be pointed out in the claims at the end of the description.

In the drawings, Figure 1 is a vertical 95 section, taken on the line I—I of Fig. 2, showing one form of smoke-house or apparatus embodying my invention. Fig. 2 is a vertical transverse section taken on the line II—II of Fig. 1. Fig. 3 is a vertical transverse section taken on the line III—III of Fig. 4. Fig. 4 is a sectional plan view taken on the line IV—IV of Fig. 3. Fig. 5 is a fragmentary transverse section showing cer-

tain of the operating mechanism in a different position from that shown in Fig. 3. Fig. 6 is an enlarged fragmentary transverse section taken on the line VI—VI of Fig. 3; and Fig. 7 is an enlarged fragmentary section through the fire-box door operating and controlling means taken on the line VII—VII of Fig. 6.

The smoke-house or apparatus may be of any desired form and of any suitable material. As shown, it consists of an outer casing 10 and an inner casing 11. The outer casing 10 has a base 12, a rear wall 13, side walls 14, and a top or roof 15, the forward portion of which has a hood 16 for the purpose of catching any vapor or smoke that may by any possibility escape to the outside of the apparatus. The rear wall 13 is provided with an opening 17 communicating with a flue 18 which leads to a chimney or other exit, and at the upper portion of said casing is a flue 19 communicating with the space under the hood 16 and which serves to direct any smoke caught by the hood toward and close to the opening 17.

A fire-box 20 is arranged within the inner casing 11 and said fire-box has an opening 20^a at the forward portion thereof which is controlled by a sliding door 21. The fire-box is provided at its sides with smoke exit openings 22 which are adapted to be closed or opened by a slide or damper 23 at each side thereof. These slides have openings which are adapted to be brought into alignment with the openings 22 to permit or prevent smoke from passing through said openings 22 into the chamber 24, the latter being located at the side and rear of the casing 11 and which chamber serves to receive the smoke to adapt the latter to pass into the opening 17 and out through the flue 18 to the chimney. At the upper portion of the fire-box 20 are one or more openings 25 forming a communication between said fire-box and the smoking chamber or compartment 26. This smoking chamber extends substantially the entire height and width of the inner casing 11 except so much thereof as is taken up by the fire-box 20, and the said smoking compartment is adapted to be shut off from the fire-box by doors 27. These doors are hinged or pivotally held at one edge, as at 28, adjacent to the side walls 29 of the inner casing and swing inwardly and downwardly inclosing so as to cover the openings 25 over the fire-box 20. While smoking the meat, the doors 27 are normally in an open position and the slides or dampers 23 of the fire-box are closed, the slide 21 covering the front opening being open or partly open for draft purposes or otherwise so that smoke from the fire-box may pass into the smoking compartment 26. When it is desired to shut off the fire-box

from the compartment 26 after the meat has been smoked, the doors 27 are closed as will be explained hereinafter, and at the same time the slides 23 are opened which will permit smoke from the fire box to pass into the outer chamber 24 about the inner casing 70 11 and up to and through the opening 17 and into the flue 18.

The smoking compartment is provided with a number of supporting bars or angular pieces 30 extending lengthwise thereof 75 which are held to the side walls 29, and at the front said compartment is open, as at 31, and is controlled by two oppositely moving sliding doors 32. The opening 31 is large enough to permit access of the workmen 80 to the smoking compartment or chamber 26 for the placing of the meat within the compartment or the removal of the same therefrom. These doors are closed when the fire-box doors 27 are open and vice versa so that 85 smoke from the fire-box cannot pass into the compartment 26 when the doors 32 are open and consequently to the outside of the apparatus so as to fill the building with the smoke issuing from the fire-box. In the top 90 or upper wall 33 of the inner casing 11 are a number of openings 34 which are controlled by a slide or chamber 35, and at the upper rear portion of the casing is an opening 36 leading to a flue 37 which communicates with the flue 18. The flue 37 is always open so that smoke can have direct and free passage to the chimney, and when the apparatus is in use, the slide or damper 35 is in a closed position while when the doors 27 100 of the fire-box are in a closed position and the doors 32 open or ready for opening, the slide 35 in that case is moved to an open position so that any smoke remaining in the smoking compartment 26 will pass not only 105 through the flue 37 but also to and from the chamber 24 and through the flue 18.

It is desirable that the doors 27 of the fire-box, the slides 23 at the side of the fire-box, as well as the slide 35 be timed with respect 110 to their movements and actuated at the same time and from a single operating shaft or other means, and such parts positively connected so that one cannot be operated independently of the other in order that no oversight on the part of the workmen or attendant will prevent the apparatus from working properly, though it will be understood that the said means may be partly or wholly controlled independently. As shown, the slides 23 are each connected to a rod 38 which is suitably guided on the casing 11, and at their outer ends said rods are connected to cranks 39. These cranks extend upward from a pivotally held rock shaft or rod 40 which is adapted to be moved back and forth and during such rocking movement force the slides lengthwise of the fire-

box to open and close the openings 22. The shaft or rod 40 has two differently positioned arms 41 and 42, the arms 42 being bifurcated at one end and provided with a roll 43. These arms 41 and 42 are arranged in the path of a horizontally arranged cam bar or arm 44. This bar or arm 44 is adapted to move bodily in a vertical direction and has one arm thereof, as 45, adapted to contact in its lowest position against the arm 41 of the crank shaft or rod 40, and its other arm 46 is provided with a cam portion 47 which is adapted to engage with the roll 43 of the arm 42. During the lowering of the arm or bar 44, the cam 47 will pass by the roll 43 and the arm 45 thereof will engage the arm 41 of the shaft 40 and rock the cranks 39 in one direction to move the slides 23 to an open position, and on the upward movement of the bar 44 the cam 47 thereof will engage the roll 43 and will move the shaft 40 and cranks 39 in the opposite direction so as to place the slides in a closed position.

The bar 44 is carried by a vertically moving rack bar 48. This rack bar 48 has the teeth thereof normally engaged by a spur gear or pinion 49 which is secured to a horizontally arranged and transversely extending shaft 50, the latter being rotatably held in lugs or brackets 51 located on the rear wall of the inner casing 11. At one end of the shaft 50 is a bevel gear or pinion 52 which meshes with a similar pinion 53. The gear 53 is held to a horizontally arranged shaft 54 which is guided in brackets or lugs 55 secured to one of the side walls of the inner casing 11. The pinion or miter gear 56 is in mesh with a larger miter gear 57 which is secured to a shaft 58 extending transversely of the apparatus and which has a part, as 59, extending on the outside of the outer wall of the casing 10. This shaft 58 has a square or otherwise formed end 60, by which a key, wrench or other tool may be used so that by rotating the same a vertical movement may be imparted to the rack bar 48 and thereby raise and lower the bar 44 and through it move the slides 23 to an open or a closed position. The upper end of the rack bar 48 is provided with a roll 61 which in its upward movement is adapted to engage with a cam action against the lower edge of the arm 62 of a bell-crank lever 63. The bell-crank lever 63 is pivoted to a bracket 64 and at one end is connected to a link or rod 65, which latter is pivoted at its inner end, as at 66, to a lug on the slide or damper 35, by which, when the bell-crank 60 is moved, the slide 35 may be moved to open or close the openings 34. The arm 62 of the bell-crank 63 is connected by a chain or other flexible connection 67 to the upper end of the rack bar 48. This chain or flexi-

ble connection 67 is of sufficient length to 65 permit the rack bar 48 to be moved a certain distance before the slack therein is taken up sufficiently to cause the chain through the bell-crank 63 to operate the link 65 and the slide 35 to place the openings 68 in said 70 slide in communication with the openings 34 of the smoking compartment.

It will thus be evident that the rotation of the shaft 58, the shaft 54 through the pinions or miter gears 52 and 53 and the 75 pinion 49, will raise and lower the rack bar 48. If the rotation is in a direction to raise the rack bar from its lowest position, it will operate the slides 23 as already described and in its upward movement will 80 cause the roll 61 to engage the bell-crank lever 63 to force the slide 35 to the position shown in Fig. 1, and at the latter part of the movement thereof, and on the downward movement of said bar, the slide will be operated at the latter part of the movement with the rack bar. This permits a quick action of the slide 35 and permits the doors 32 to remain locked as long as possible.

A link 69 is connected at one end to a pin 90 70 projecting outwardly from one of the fire-box doors 27. This pin passes through a curved slot 71 extending in the arc of a circle with the hinge of said door as a center. A second link 72 similar to the link 69 95 is pivotally held to a pin 73 projecting outward from the other fire-box door 27. This pin also projects through a slot 74 similar to the slot 71 and forming an arc of a circle with the hinge of the other fire-box door as 100 a center. These links 69 and 72 are pivotally held at their inner ends to a bolt 75 which passes through the lower end of the rack bar 48 and the bar 44. During the downward movement of the rack bar 48, the 105 inner ends of the links will be forced downward and the outer end of said links will be forced inward and downward corresponding to the curvature of the slots 71 and 74 to the position shown in Fig. 5, carrying 110 therewith the doors of the fire box to a horizontal and closed position as shown in dotted lines in said figure. This downward movement of the rack bar also operates the crank rock shaft 49 at the extreme end of the movement in one direction and in its upward movement will operate the rock shaft 40 in the opposite direction by engagement of the cam 47 with the roll 43 as already explained, and as the bar 48 continues 115 upward, it will force the upper ends of the links 69 and 72 outward carrying therewith the fire-box doors 27 upward to an open position.

To automatically lock or unlock the doors 120 32 simultaneously with the movement of the slide 35, various means may be employed. As shown, each of the doors has an inwardly

extending plate 76. These plates are each provided with an opening 77 and are adapted to be brought into alinement when the doors are in a closed position. These openings are adapted to be engaged by a pin or bolt 78 which is guided in the upper wall 33 of the inner casing 11 and is connected at its upper end to a lever 79. This lever 79 is pivoted at 80 to a pendent bracket 81 and has its outer end bent upward to form a cam portion 82. On the slide or shutter 35 is an upright 83 through which extends a pin 84. When the slide 35 is forced rearward by the link 65 to place the openings 15 68 and 34 in alinement, the pin 84 riding along the cam portion 82 of the lever 79 will force the forward end of said lever upward so as to move the bolt 78 out of engagement with the openings 77 of the doors 32, thus releasing the same which will permit the doors to be opened. On the reverse movement of the slide 35 and when the doors are closed, the bolt 78 will be permitted to lower by gravity to engage said openings, 25 though a spring may be provided tending normally to hold the bolt 78 in a lowered position. By this means the doors cannot be opened without the movement of the slide 35 and as the slide is connected to be operated with the means which also operates the fire-box doors and the slides 23, the said doors of the smoking compartment cannot be opened except that the said fire-box doors and the smoke exit controlling means are in 35 their proper relative positions.

The invention will be readily understood from the foregoing description when taken in connection with the accompanying drawings. The meat to be smoked having been placed in the smoking compartment or chamber 26 by being suspended in any suitable way along the bars 30, and the shaft 58 operated by a suitable tool to position the parts as shown in Fig. 1, the smoke from the fire-box 20 will pass upward through the smoking compartment and out through the flue 37 to the flue 18 and from there to the chimney. In this position the doors 32 for access of the workmen to the smoking compartment, are locked by the bolt 78. If the shaft 58 be now rotated in the opposite direction by a key, wrench or otherwise, the rack bar 48 will be forced downward and as it lowers it will close the fire-box doors 55 27 shutting off the communication between the fire-box and the smoking compartment. At the extreme movement of the rack bar 48, the bar 44 will engage the arm 41 so as to force the slides 23 forward to bring the 60 openings in said slides in alinement with the openings 22 of the fire-box. This downward movement of the rack bar 48 through the flexible connection or chain 67, will move the slide or shutter 35 rearward placing the 65 openings 34 and 68 in alinement, and at the

same time causing the pin 84 to move the lever 79 on its pivot to release the bolt 78. As the fire-box doors 27 during the downward movement of the rack bar 48 through the links 69 and 72 are closed, no smoke 70 from the fire-box can enter the smoking compartment, but the lateral openings 22 at this time form smoke exit openings to permit the smoke from the fire-box to enter the outer chamber 24 through which the smoke 75 will pass into the flue 18. Any smoke that may remain in the smoking compartment or which has passed therein during the closing of the fire-box doors 27, will be caused to pass not only out through the flue 37 but 80 will pass also through the openings 34 and 68 to the flue 18, thus when the doors 32 are open, there is no smoke to pass out of the apparatus into the room or place where the apparatus is located. The meat already 85 smoked may be removed and other meat placed in the smoking compartment, and after the doors are closed the rack bar 48 may be again operated to force the parts to the position shown in Fig. 1 when the apparatus is again in operative condition. 90

It will be evident that by the construction shown there will be no smoke left in the smoking compartment when the parts are operated to unlock the doors 32 and in this 95 way the workmen are not liable to injury by inhaling the smoke when they enter said smoking compartment. It will be evident also that the outer chamber 24 by forming an air space about the fire-box and the 100 smoking compartment, there is less liability to fire by the heated surfaces coming into contact with anything, and this poor-heating space or chamber has a tendency to cool the smoke and thereby assists in preventing 105 shrinkage of the meats.

While the invention has been shown and described as formed of sheet metal to adapt the same to be placed within a building as an entirety, it is to be understood that the 110 walls forming the inner and outer compartments of the device may be made of masonry or a combination of masonry and metal or otherwise without departing from the nature of the invention. It will be also 115 understood that instead of the mechanism shown for operating the various slides and doors, any suitable mechanism may be employed.

From the foregoing, it will be evident that 120 a simple and efficient smoke-house or apparatus is provided whereby meats may be effectually smoked without permitting any of the smoke or vapors to pass into the room or building where the apparatus is located; that simple means is provided whereby all the operative parts are so connected that by the operation of one, the other operative parts are placed in their proper relative positions; that simple means is provided 125 130

whereby the smoking compartment may be entirely cut off from the fire-box; that simple means is provided whereby the doors for the workmen for access to the smoking compartment may be automatically locked or unlocked; and that said apparatus is simple in construction.

Having thus described my invention, I claim as new and desire to secure by Letters Patent:—

1. A smoke-house comprising an inner casing having a fire-box and a smoking compartment each having smoke exit openings, means for suspending the material to be smoked within the smoking compartment, an outer casing spaced from the inner casing to form an outer chamber thereabout, independent flues leading from the smoking compartment and from the outer chamber, said smoking compartment having a large opening for access by the workmen to the smoking compartment, doors controlling the access opening to said smoking compartment, doors for the fire-box to prevent smoke from entering the smoking compartment or to permit smoke to enter therein, means for closing said smoke exit openings of the fire-box and the smoking compartment, mechanism for controlling the position of the closing means of the smoke exit openings for automatically locking and unlocking the access doors of the smoking compartment, and means for opening or closing the doors of the fire-box.

2. A smoke-house comprising an inner casing having a fire-box and a smoking compartment each having smoke exit openings, means for suspending the material to be smoked within the smoking compartment, an outer casing spaced from the inner casing to form an outer chamber thereabout, means for conveying the smoke from the smoking compartment and from the outer chamber, said smoking compartment having a large opening for access by the workmen to said smoking compartment, doors controlling the access opening to said smoking compartment, doors for the fire-box to prevent smoke from entering the smoking compartment or to permit smoke to enter therein, means for closing said smoke exit openings of the fire-box and the smoking compartment, means for controlling the position of the closing means of the smoke exit openings, means for locking or unlocking the access doors of the smoking compartment, and means for opening or closing the doors of the fire-box.

3. A smoke-house having a fire-box and a smoking compartment each provided with smoke exit openings, an outer casing providing an outer chamber about the smoking compartment, flues leading from the smoking compartment and from the outer chamber, said smoking compartment having a

large opening for access by the workmen to said smoking compartment, means controlling the access opening to said smoking compartment, doors for closing the fire-box to prevent smoke from entering the smoking compartment or to permit smoke to enter therein, and means for closing said smoke exit openings of the fire-box and doors leading to the smoking compartment.

4. A smoke-house having an inner casing having a fire-box and a smoking compartment and having smoke exit openings, means for suspending the material to be smoked within the smoking compartment, an outer casing spaced from the smoking compartment to form an outer smoke chamber thereabout, independent flues leading from the smoking compartment and from the outer chamber, said inner smoking compartment having an access opening to the smoking compartment, doors controlling the access opening to said smoking compartment, means for closing said smoke exit openings of the fire-box and the smoking compartment, and mechanism for controlling the position of the closing means of the smoke exit openings and for automatically locking or unlocking the access doors of the smoking compartment.

5. A smoke-house comprising an inner casing having a fire-box and a smoking compartment each having smoke exit openings, an outer casing spaced from the inner casing to form an outer smoke chamber thereabout, means for conveying the smoke from the smoking compartment and from the outer chamber, said smoking compartment having a large opening for access by the workmen to said smoking compartment, doors for closing the fire-box to permit smoke from entering the smoking compartment, and means for closing said smoke exit openings of the fire-box and the smoking compartment and for simultaneously closing the fire-box doors.

6. A smoke-house having a fire-box and a smoking compartment, an outer casing spaced from the inner casing to form an outer chamber thereabout, means for conveying smoke from the smoking compartment and from the outer chamber, said inner smoking compartment having a large opening for access by the workmen to the smoking compartment, doors controlling the access opening to said inner smoking compartment, means for closing said smoke exit openings of the fire-box and the smoking compartment, and mechanism for controlling the position of the closing means of the smoke exit openings.

7. A smoke-house having a fire-box and a smoking compartment provided with independent smoke exit openings, separate means for controlling said openings, doors adapted to shut off or to permit smoke to enter said

70

compartment from the fire-box, means for conveying the smoke away from the smoking compartment and from the fire-box, and means for operating the fire-box doors and 5 for operating both of the smoke exit controlling means.

8. A smoke-house comprising an inner casing having a fire-box and a smoking compartment each having smoke exit openings, 10 means for suspending the material to be smoked within the smoking compartment, an outer casing spaced from the inner casing to form an outer chamber thereabout, independent flues leading from the smoking compartment and from the outer chamber, said smoking compartment having a large opening at the front thereof for access by the workmen to the smoking compartment, doors controlling the access opening to said smoking compartment, doors for closing the fire-box to prevent smoke from entering the smoking compartment or to permit smoke to enter therein, means for simultaneously closing said smoke exit openings of the fire-box 25 and the smoking compartment and for moving the doors of the fire-box to an open position or vice versa, and for automatically locking or unlocking the access doors of the smoking compartment during the operation 30 of the fire-box doors and the controlling means of the smoke exit openings.

9. A smoke-house comprising a casing having a smoking compartment and a fire-box and having an opening for access to said smoking compartment, means for shutting off the fire-box from the smoking compartment, doors adapted to close said opening, and means operatively connected to the fire-box shutting off means for locking and 40 unlocking said doors.

10. A smoke-house comprising a casing having a smoking compartment and a fire-box and having an opening for access to said smoking compartment, means for shutting off the fire-box from the smoking compartment, means adapted to close said opening, and means operatively connected to the fire-box shutting off means for locking and unlocking said opening and closing means.

50 11. A smoke-house having a fire-box and a smoking compartment, the latter being provided with an opening for access to said smoking compartment, doors adapted to close said opening, doors for shutting off said fire-box from the smoking compartment, manually operated means for opening and closing said doors, and means operatively connected to the fire-box door operating means for locking and unlocking said doors.

60 12. A smoke-house comprising an inner casing having a smoking compartment and a fire-box, means for closing communication between the fire-box and the smoking compartment, an outer casing having a chamber about the smoking compartment, said smok-

ing compartment having smoke exit openings at the upper part thereof and an access opening at the front portion thereof, a slide controlling said smoke exit openings, a pair of sliding doors controlling the access opening at the front portion thereof, a locking bolt adapted to be brought into and out of engagement with said doors, a lever having a cam portion to which said bolt is held, means movable with the slide adapted to engage said lever to move the latter to shift the position of the bolt, and means for operating the slide. 70 75

13. A smoke-house comprising an inner casing having a smoking compartment, an outer casing having a chamber about the smoking compartment, said smoking compartment having smoke exit openings at the upper part thereof and an access opening at the front portion thereof, a slide controlling 80 85 said smoke exit openings, means controlling the access opening at the front portion thereof, a locking bolt adapted to be brought into and out of engagement with said means, a lever having a cam portion to which said bolt is held, means movable with the slide adapted to engage said lever to move the latter to shift the position of the bolt, and means for operating the slide. 90 95

14. A smoke-house comprising an inner casing having a smoking compartment provided with exit openings at the upper part thereof and with an access opening at the front portion thereof, a slide controlling said smoke exit openings, a pair of sliding doors 100 controlling the access opening at the front portion thereof, and means operated by the slide for locking and unlocking said doors.

15. A smoke-house comprising an inner casing having a smoking compartment provided with smoke exit openings at the upper part thereof and with an access opening at the front portion thereof, a slide controlling said smoke exit openings, means controlling the access opening at the front portion thereof, and means for locking and unlocking 105 110 said controlling means.

16. In a smoke-house, the combination of a casing provided with a smoking compartment, means for causing smoke to pass into said compartment, means for conveying smoke away from said compartment, said compartment having smoke exit openings at the upper part thereof, a slide controlling said openings, a bell-crank lever, a vertically movable rack bar adapted to actuate said lever in one direction, a flexible connection between the rack bar and the bell-crank lever for operating said lever in the opposite direction, and means for moving said 115 120 rack bar.

17. In a smoke-house, the combination of a casing provided with a smoking compartment, means for causing smoke to pass into said compartment, means for conveying 130

smoke away from said compartment, said compartment having smoke exit openings at the upper part thereof, a slide controlling said openings, a bell-crank lever, and means 5 for operating said lever in opposite directions.

18. In a smoke-house, the combination of a casing provided with a smoking compartment, means for causing smoke to pass into 10 said compartment, means for conveying smoke away from said compartment, said compartment having smoke exit openings, a slide controlling said openings, a bell-crank lever, a vertically movable rack bar 15 adapted to actuate said lever in one direction, a connection between the rack bar and the bell-crank lever for operating said lever in the opposite direction, and means for moving said rack bar.

20 19. In a smoke-house, the combination of an inner casing having a smoking compartment and a fire-box, an outer casing forming a chamber about the fire-box and smoking compartment, said fire-box having openings 25 leading to the smoking compartment and with lateral openings communicating with the outer chamber, doors controlling the openings leading to the smoking compartment, slides for controlling the lateral 30 openings leading to the outer chamber, a crank shaft operatively connected to the slides and having two arms differently positioned with respect to each other, a bar 35 adapted to engage said arms to move the rock shaft in opposite directions to open and close the lateral openings of the fire-box, and means connecting said bar to the fire-box doors to open and close the same, said fire-box doors being open when the slides 40 are moved to a closed position and vice versa.

20. In a smoke-house, the combination of an inner casing having a smoking compartment and a fire-box, an outer casing forming a chamber about the fire-box and smoking compartment, said fire-box having openings leading to the smoking compartment and to the outer chamber, means controlling 45 the smoking compartment communicating means, slides for controlling the lateral 50 openings leading to the outer chamber, a crank shaft operatively connected to the slide and having two arms differently positioned with respect to each other, and means 55 adapted to engage said arms to move the rock shaft in opposite directions to open and close the lateral openings of the fire-box.

21. In a smoke-house, the combination of

an inner casing having a smoking compartment and a fire-box, an outer casing forming a chamber about the fire-box and smoking compartment, said fire-box having openings leading to the smoking compartment and with lateral openings communicating with the outer chamber, doors controlling 60 the openings leading to the smoking compartment, slides for controlling the lateral 65 openings leading to the latter chamber, and means for opening the doors when the slides are closed and vice versa.

22. In a smoke-house, the combination of an inner casing having a smoking compartment and a fire-box, an outer casing forming a chamber about the fire-box and smoking compartment, said fire-box having openings leading to the smoking compartment and with lateral openings communicating with the outer chamber, doors controlling the openings leading to the smoking compartment, slides for controlling the lateral 75 80 openings leading to the latter chamber, a crank shaft operatively connected to the slide and having two arms, a vertically movable element adapted to engage said arms to move the rock shaft in opposite directions 85 to open and close the lateral openings of the fire-box, and means connecting said element to the fire-box doors to open and close the same.

23. In a smoke-house, the combination of 90 an inner casing provided with a smoking compartment and a fire-box, an outer casing provided with a chamber about the smoking compartment, fire-box doors adapted to shut off or permit communication between the 95 fire-box and the smoking compartment, a vertically movable bar, means for moving said bar, and links connecting said bar to the doors to open and close the same.

24. In a smoke-house, the combination of 100 an inner casing provided with a smoking compartment and a fire-box, an outer casing provided with a chamber about the smoking compartment, fire-box doors adapted to shut off or permit communication between the 105 fire-box and smoking compartment, a vertically movable element, means for moving said element, and links connecting said element to the doors to open and close the same.

This specification signed and witnessed 110 this 22nd day of April A. D. 1914.

JACOB F. OBERLE.
